His atty.

UNITED STATES PATENT OFFICE.

FRANK G. WALTZ, OF TOLEDO, OHIO, ASSIGNOR, BY MESNE ASSIGNMENTS, TO THE
TOLEDO BUTTON MACHINE COMPANY, OF TOLEDO, OHIO, A CORPORATION OF OHIO.

BUTTON-FEED CONTROL.

1,218,139.

Specification of Letters Patent.

Patented Mar. 6, 1917.

Application filed January 10, 1916. Serial No. 71,385.

To all whom it may concern:

Be it known that I, FRANK G. WALTZ, a citizen of the United States, and a resident of Toledo, in the county of Lucas and 5 State of Ohio, have invented a certain new and useful Button-Feed Control; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates particularly to means for controlling the feed of buttons from the button containing hopper to the button feed chute or tube of a shoe button fastening machine.

20 The object of my invention is the provision of simple and improved control means of the character described which is easily and quickly adjustable both to act as a stop for preventing the feed of buttons from the feed hopper to the button feed chute or tube, and as a means for regulating the size of buttons permitted to be fed to the feed chute, or in other words, only permitting buttons under a predetermined size to be delivered to the feed chute.

25 The invention is fully described in the following specification, and while, in its broader aspect, it is capable of embodiment in numerous forms, a preferred embodiment 30 thereof is illustrated in the accompanying drawings, in which,—

35 Figure 1 is a side elevation of the means embodying my invention in operative button feeding relation to the associated parts 40 of the machine, with parts of the machine broken away and in section. Fig. 2 is a similar view thereof with the control means in button stop position with respect to the associated parts, and Fig. 3 is a fragmentary top plan view of the control means and associated parts.

45 Referring to the drawings, 1 designates a frame part forming a button hopper 2 in which a button raising slide 3 is mounted for vertical reciprocatory movements being 50 operated in any suitable manner, as is well understood in the art. The slide 3 has its top surface rearwardly inclined and provided with a longitudinally extending

groove 4 for receiving the eyes of buttons 55 5, which are raised from the bottom portion of the hopper by the slide on an upward movement thereof. When the slide is at the limit of its upward movement the lower front end of the groove or race-way 60 4 registers with a corresponding groove or race-way 6 in the frame part 1, or upper front portion of the hopper wall so that buttons having their eyes projected into the slide groove 4 are permitted to feed downward and forward by gravity through the registering grooves 4—6 and into the button chute or tube 7, which registers with and leads downward and forward from the forward end of the frame race-way 6, as is 65 well understood in the art. It is customary to make the chute 7 removable so that one chute may be substituted for another as it may be desired to feed buttons of different sizes, or for some other purpose. 75

The control means comprising my invention is illustrated, in the present instance, as comprising a lever member 8, which is disposed over the frame race-way 6 and pivoted to the upper portion of said frame, as at 80 9, for vertical rocking movements relative thereto and in vertically spaced relation to the top edge of the race-way 6. The forward end of the lever 8 is of concaved or transversely dished form to adapt it to seat 85 down over the top rounded surface of the button chute 7 at the rear end thereof, as shown in Fig. 1. The opposite or rear end of the lever 8 is preferably transversely broadened or enlarged, as best shown in Fig. 90 3, and the rear edge thereof is inclined or diagonally disposed with respect to the lever axis, as at 10. The purpose of making the rear end of the lever in this form is to cause 95 any button or buttons which may be improperly positioned on the top of the slide 4, or the rear end portion of the grooved surface of the frame 1, to be directed from the grooved surface of the frame transversely thereof and permitted to fall back 100 into the hopper at a side of the slide 3. In other words, it is necessary for the buttons to have the eyes thereof projected into the groove 4—6 in order to pass from the hopper into the chute 7. If a button which is 105 elevated by the slide 3 does not have its eye engaged within the groove 4 thereof or does not engage within the rear end portion of

the groove 6, such button will be forced back into the hopper by contact with the inclined rear edge 10 of the lever.

A threaded stud 11 projects upward in advance of the lever pivot 9 and at one side of the lever and extends through a registering opening in a transverse ear or extension 12 on the edge of the lever. A nut 13 is threaded on the stud 11 at the outer side of the lever and is adjustable on the stud to regulate the position of adjustment of the lever, as is apparent. A coiled compression spring 14 is disposed around the base portion of the stud 11 between the lever and frame and exerts an upward pressure on the forward end portion of the lever to retain it in contact with the nut 13 during a pre-determined range of adjustment of such nut.

It is evident that if it is desired to stop the feed of buttons from the hopper to the chute 7, it is only necessary to turn the nut 13 outward on the stud 11, as the spring 14 acts to raise the forward end of the lever and to lower its rear end into button obstructing position with respect to the groove 6. It is also evident that the rear end of the lever may be raised any desired extent from the grooved surface of the frame to accommodate the size of button which it is desired to feed to the chute, and preventing buttons of a larger size from feeding forward through the groove 6.

I wish it understood that my invention is not limited to any specific construction, arrangement or form of the parts, as it is capable of numerous modifications without departing from the spirit of the claims.

Copies of this patent may be obtained for five cents each, by addressing the "Commissioner of Patents, Washington, D. C."

Having thus described my invention, what I claim as new, and desire to secure by Letters Patent, is,—

1. In a machine of the class described, the combination with a feed hopper having a button delivery way, of a member pivoted above said way, and means operable to adjust said member with respect to said way to place it in button feeding or button stop positions, said member having its rear end shaped to direct transversely from said way buttons which are not properly positioned thereon for feeding.

2. In a machine of the class described, the combination with a feed hopper having a button delivery way, and a chute leading from the forward end of said way, of a lever member pivotally mounted over said way and adapted to rest at its forward end on the rear end portion of said chute and adapted to be adjusted to control or stop the feed of buttons through said way and into said chute, and means operable to adjust said member.

3. In a machine of the class described, the combination with a hopper having a button delivery way, of a feed control member pivoted over said way for vertical oscillatory movements with respect thereto, a stud projecting from a part of said member, a nut threaded onto said stud over said member, and compression means disposed below said member in opposition to said nut.

In testimony whereof, I have hereunto signed my name to this specification.

FRANK G. WALTZ.
